United States Patent Office

Des. 185,380
Patented June 2, 1959

185,380

ROTATABLE DISPLAY STAND

Joseph H. Meyer, Rockville Centre, N.Y., assignor to
Joseph H. Meyer Bros., Brooklyn, N.Y., a corporation
of New York

Application August 27, 1958, Serial No. 52,397

Term of patent 14 years

(Cl. D80—10)

FIG. 1.

FIG. 4.

FIG. 5.

FIG. 2

FIG. 3

Fig. 1 is a side elevational view of a rotatable display stand showing my new design.

Fig. 2 is a top plan view thereof.

Fig. 3 is a bottom plan view thereof, with the top broken away for convenience of illustration.

Fig. 4 is a cross-sectional view taken on line 4-4 of Fig. 3.

Fig. 5 is a cross-sectional view taken on line 5-5 of Fig. 3.

I claim:

The ornamental design for a rotatable display stand, as shown.
